UNITED STATES PATENT OFFICE

JOHN H. LAWRENCE, OF NEW YORK, N. Y., AND JAY A. FREIDAY, OF EAST ORANGE, NEW JERSEY, ASSIGNEES, BY MESNE ASSIGNMENTS, TO METROPOLITAN ENGINEERING COMPANY, A CORPORATION OF NEW YORK

BOILER

Application filed June 18, 1925. Serial No. 37,915.

In a previous application of Murray and Lawrence, No. 719,696 there is described a boiler having a furnace with one or more walls of vertical water tubes with a special 5 circulating system. The present invention is directed to certain improvements in such a boiler and particularly in the circulating system thereof. The accompanying drawings illustrate an embodiment of the invention.

10 Fig. 1 is a longitudinal section of a complete boiler;

Fig. 2 is a transverse section of one half of the same;

15 Fig. 3 is a perspective view of a detail of the tubes forming the water walls.

Referring to the embodiment of the invention illustrated, the furnace is enclosed within a front wall 1, offset from the boiler tubing, at the upper end of which is a horizontal wall 20 or arch 2 with openings through which pass burners 3 of the nozzle type for projecting jets of powdered coal, oil or gas into the combustion chamber. These walls, and the rear wall 4 and side walls 5 (Fig. 2) are of any 25 usual or suitable construction and material.

Above the combustion chamber are the usual inclined, approximately horizontal, boiler tubes 6 and the superheater tubes 7, with baffles for directing the gases of combustion to heat the tubes by convection and to 30 direct them out finally by the smoke pipe 8 to the exhaust fan or stack; these tubes being also enclosed in walls of any usual or suitable construction and material.

35 The approximately horizontal tubes above the combustion chamber are supplemented by sets of vertical tubes 9 at the sides and similar tubes 10 at the rear of the combustion chamber and exposed directly to the radiant heat 40 of the burning fuel. Preferably, as described in previous applications of Murray, No. 678,443 and others, the tubes 9 and 10 are of the kind illustrated in Fig. 3, with longitudinal fins 11 welded thereto and over- 45 lapping each other so as to cover the spaces between the tubes, to entirely shield the enclosing walls of masonry and to be exposed to the heating gases on the inner side only of the water wall. These fins provide in effect 50 a greatly increased surface of conducting ma-

terial exposed to the radiant heat of the furnace and transmitting such heat by conduction to the water within the tubes, and thus greatly increase the efficiency of the boiler as a whole.

55 Because of the high rate at which the water in these tubes is converted into steam, it is particularly important for efficiency and also to prevent explosions, that they be provided with a reliable circulating system. The set of vertical tubes 9 at each side of the furnace is connected with top and bottom headers 12 and 13 respectively. The water is supplied to the bottom headers as herein-after described and passes thence up through the vertical tubes, out through the top header and thence by way of pipes 14 to the opposite ends of a header 15 and through pipes 16 to a steam drum 17. The water from the drum passes down through pipes 18 and headers 19 and 20 to the lower ends of the approximately horizontal tubes; and from the vertical headers 20 to a horizontal header or mud drum 21, from the ends of which it is discharged into inclined pipes 22 leading 70 from the front to the back of the boiler and discharging into vertical pipes 23 which enter the rear ends of the lower headers 13 previously referred to.

75 A separate circulation is provided for the tubes 10 of the rear wall. The water enters by way of the header 24 connected to their lower ends. Each of the tubes 10 at its upper end enters one of the vertical headers 25 at the ends of the horizontal tubes 6 which communicate by pipes 26 with similar headers 27 for the second bank of horizontal tubes, which communicate in turn with pipes 28, leading to the steam drum 17. The water passes out from the drum 17 through downwardly inclined pipes 29 to loops 30 and thence by vertical pipes 31 to a header 32 extending across the front of the boiler. From the header 32 the water passes first through pipes 33 constituting a water screen for the cinders which fall from the combustion chamber and thence to the header 24 at the bottom of the rear water wall.

80 The steam from the drum passes out through pipes 34 to the superheater tubes 7 100

and thence to the point of consumption. A blow-off is indicated at 35 for the bottom header of the tubes 9. Other blow-offs, inlets for water, valves and so forth may be provided as required. Separate steam drums may be used as described in application 719,696 for example.

The connection of the rear wall tubes 10 directly with the headers of the horizontal tubes provides a shorter and easier path for the ascending water and steam than where a cross header is interposed, and thus secures an improved circulation.

The invention is of particular importance 15 in connection with the spaced flanged tubes shown. With this construction the surface exposed to the heat is so great in proportion to the size of the column of water in the tubing that the latter is heated at a very much more 20 rapid rate than in the ordinary design of boilers and it becomes more than ordinarily necessary to provide a free and easy circulation through these tubes.

Various modifications of the design and arrangement shown may be made by those skilled in the art without departing from the invention as defined in the following claims.

What we claim is:

- 30 1. A boiler having a furnace with a plurality of water walls composed of vertical tubes exposed to the radiant heat of the burning fuel and having horizontal tubes above the furnace heated by convection from the furnace gases, said tubes having inlet and outlet headers and separate circulating systems for said water walls, one system including said inlet headers only and another including said outlet headers only.
- 40 2. A boiler having a furnace with opposite side walls of vertical water tubes and an end wall of vertical water tubes, exposed to the radiant heat of the burning fuel, and having horizontal tubes above the furnace heated by convection from the furnace gases, said tubes having inlet and outlet headers and separate circulating systems for said water walls, one system including said inlet headers only and another including said outlet headers only.
- 50 3. A boiler having a furnace in which are, first, a set of water tubes forming water walls exposed to the radiant heat of the burning fuel and, second, a set of water tubes beyond the furnace heated by convection from the furnace gases, said tubes having inlet and outlet headers and separate circulating systems for said water walls, one system including said inlet headers only and another including said outlet headers only.
- 60 4. A boiler having first a set of water tubes exposed to the radiant heat of the burning fuel, said tubes being spaced apart and provided with flanges in the intervening spaces so as to generate steam at a high rate and to 65 require a rapid circulation, and having, sec-

ond, a set of tubes beyond the furnace heated by convection from the furnace gases, and having headers on the inlet and outlet ends of the second set of tubes, and separate circulating systems for different groups of the first set of tubes, one of said circulating systems including only the aforesaid inlet headers and the other including only the aforesaid outlet headers.

5. A boiler having a furnace with a first set of water tubes exposed to the radiant heat of the burning fuel and a second set of water tubes beyond the furnace heated by convection from the furnace gases, having headers on the inlet ends and the outlet ends of the second set of tubes and a first circulating system including inlet headers of the second set of water tubes, a connection between such headers and the inlets of certain water tubes of the first set and a direct connection from the outlets of the last named water tubes to the steam drum, and a second circulating system including outlet headers of the second set of water tubes, a connection between such headers and the outlets of certain other water tubes of the first set and a direct connection from the steam drum to the inlets of the last named water tubes.

6. A boiler having a furnace with a first set of water tubes exposed to the radiant heat of the burning fuel, a second set of water tubes beyond the furnace heated by convection from the furnace gases and inlet headers and outlet headers at the ends of said second set of tubes, said boiler including a steam drum and having two circulating systems, the first system leading from the drum through said inlet headers and outside of the furnace to the inlet ends of certain of the first set of water tubes and through such tubes to the drum and the second system leading from the drum to the inlets of certain others of the first set of water tubes and through such tubes to the outlet headers of the second set and thence to the drum.

In witness whereof, we have hereunto signed our names.

JOHN H. LAWRENCE.
JAY A. FREIDAY.
